DESIGN.

—o—
N. L. SÉGUIN.

PARASOL OR UMBRELLA TOP.

No. 16,597.

Patented Mar. 30, 1886.

UNITED STATES PATENT OFFICE.

NORCOM L. SÉGUIN, OF PHILADELPHIA, PENNSYLVANIA.

DESIGN FOR A PARASOL OR UMBRELLA TOP.

SPECIFICATION forming part of Design No. 16,597, dated March 30, 1886.

Application filed January 23, 1886. Serial No. 189,530. Term of patent 3½ years.

To all whom it may concern:

Be it known that I, NORCOM L. SÉGUIN, a citizen of the United States, residing in the city and county of Philadelphia, State of Pennsylvania, have invented and produced a new and original Design for Parasol or Umbrella Tops, of which the following is a specification, reference being had to the accompanying photographic illustration, forming part thereof.

5 The leading feature of my design for a parasol or umbrella top is the representation of a twisted corded surface of said top.

10 A represents the top of a parasol, the same presenting a globular or rounded appearance, having across its face B the representation of twisted cords, shown in contact, the lines of which are parallel to each other and slightly inclined to the sides of the top. The lines of 15 the representation of the twisted strands are

also parallel to each other, as is readily seen 20 in the drawing. The twisted cord representation is also shown across the neck of the parasol, having a similar appearance thereon to that on the top thereof.

15 I claim—

The design for a parasol or umbrella stick herein shown and described, the same consisting of a stick having the upper extremity terminating in a globe or sphere, the surface of which sphere has the conventional representation of a twisted cord passing in spiral form from the upper to the lower pole and covering the entire surface thereof, as set forth.

25 NORCOM L. SÉGUIN.
